WALTER A. BATES, OF GARY, INDIANA, ASSIGNOR TO WALTER BATES STEEL CORPORATION, OF GARY, INDIANA, A CORPORATION OF DELAWARE

EARTH ANCHOR

Application filed August 23, 1928. Serial No. 301,477.

The present invention relates to earth anchors.

More particularly, the present invention relates to means for anchoring poles and similar structure, and has for one of its objects the provision of anchoring means which is simple and cheap to install and effective in service.

A further object is to provide an earth anchor which involves the drilling of a hole relatively small in diameter but which provides an effective anchorage.

A further object is to provide an improved method of anchoring a member within the earth.

A further object is to provide an improved method of anchoring members within the earth.

Further objects will appear as the description proceeds.

Referring to the drawings—

Figure 1 represents a tower having its legs secured by means of earth anchors embodying the principles of the present invention;

Figure 2 is a view shown on a larger scale than that of Figure 1, showing the earth anchor inserted in the earth and before it has been expanded into gripping relationship with the earth;

Figure 3 is a view showing an earth anchor embodying the principles of the present invention in expanded gripping relationship with the earth and having a section of the tower secured to said earth anchor; and

Figure 4 shows a slight modification.

For the purpose of illustrating the present invention, a tower 10 has been illustrated, which tower has a plurality of legs 11—11, 40 which legs are illustrated as being angles. It will be understood of course that the cross-sectional contour of the legs 11—11 may take any preferred form and the anchor comprising the present invention will have a corresponding form. For purposes of this description, however, an angular form of leg will be described.

The earth anchor comprising the present invention comprises a tube 12 provided with 50 a plurality of slits 13—13 extending longi-

tudinally thereof, providing lacings 14—14. Said slits 13—13 should preferably be of equal length, equally spaced around the periphery of the tube 12 and equally spaced from the extremities of said tube 12. Said 55 slits should terminate a short distance away from the bottom end of said tube 12, leaving a band 15 at the lower end of said tube. Above said slits 13—13 the tube is imperforate for a considerable distance, as indicated 60 by the numeral 16. The top portion of the tube 12 is formed for the attachment of a leg 11. In the embodiment illustrated in Figures 2 and 3, substantially one-half of the tube has been cut away and the remaining 65 portion has been swaged into angular form having two walls 17 and 18. Said walls 17 and 18 are provided with bolt holes 19—19 for attachment to corresponding legs 11—11 of the tower 10. In the embodiment in Figure 4, the top portion of the tube is not cut away, said top portion being merely swaged 70 to provide the flat walls 20 and 21 disposed in angular relationship with one another, which walls 20 and 21 are provided with the 75 bolt holes 19.

The hole in the earth in which the tube 12 is mounted may be of substantially the same diameter as the tube 12, or may be larger if preferred. In either case, after the 80 tube 12 has been inserted into the earth, a charge of dynamite is lowered into said tube and disposed within the lacings 14—14 near the bottom end of said tube. The dynamite is then exploded, which explosion forces back 85 the earth, compressing same, and expands the lacings 14—14, substantially as shown in Figure 3. Concrete is then poured down through the tube 12, and if said tube is disposed in a hole of greater diameter than said tube, said concrete will also be poured down said hole outside of said tube. Said concrete will form a ball, indicated by the numeral 22, within the region provided by the explosion of the dynamite. Regardless 90 of the relative diameters of the tube 12 and the hole in which it is disposed, said concrete will flow out around the lacings 14—14, providing a firm grip upon the tube 12. As 95 appears from an inspection of Figure 3, the 100

force of the explosion is not sufficient to disrupt the lacings 14—14.

The earth anchor illustrated and described is strong both in tension and compression. A decided advantage of the present invention is that the lacings 14—14, after having been expanded by the explosion, would tend to retain the earth until the concrete is poured, a decided advantage especially in soft or marshy ground.

10 Though certain preferred embodiments of the present invention have been described in detail, many modifications will occur to those skilled in the art. It is intended to 15 cover all such modifications that fall within the scope of the appended claims.

What is claimed is—

1. The method of anchoring which consists of expanding the lacings of a slotted 20 tube intermediate of the length thereof within the earth by means of an explosion whereby to force back said earth and to expand said lacings into position to keep back said earth, and pouring concrete or the like into 25 said tube to fill the recess provided by said exploding operation and to imbed said lacings.

2. An earth anchorage comprising a tube disposed within the earth, said tube having 30 intermediate of its length but adjacent to one of its extremities lacings disposed outwardly of the diameter of said tube and a concrete ball disposed within and embedding said lacings.

35 3. The method of anchoring which comprises mounting a tube within a hole in the earth, exploding a charge within an embedded portion of said tube to expand portions thereof without disrupting the same 40 and to force back the earth adjacent to said portions, and filling the region provided by said exploding operation with concrete or the like.

Signed at Gary, Indiana, this 20th day of 45 Aug., 1928.

WALTER A. BATES.
